UNITED STATES PATENT OFFICE.

ROBINSON H. HOWELL, OF HAMMONDSPORT, NEW YORK.

DESIGN FOR A TOY AIRSCOUT.

57,128.

Specification for Design.

Patented Feb. 22, 1921.

Application filed December 1, 1919. Serial No. 341,818. Term of patent 3½ years.

To all whom it may concern:

Be it known that I, ROBINSON HOWELL Howell, a citizen of the United States, residing at Hammondsport, in the county of Steuben and State of New York, have invented a new, original, and ornamental Design for a Toy Airscout, of which the following is a specification, reference being had to the accompanying drawings, forming a part thereof.

The figure is perspective view of the toy airscout, showing my new design.

I claim:

The ornamental design for a toy airscout, as shown.

R. H. HOWELL.
